UNITED STATES PATENT OFFICE.

ALPHONSO E. PEPPE, OF NEW YORK, N. Y.

CAN-CARRIER.

1,080,578.

Specification of Letters Patent.

Patented Dec. 9, 1913.

Application filed April 5, 1913. Serial No. 759,143.

To all whom it may concern:

Be it known that I, ALPHONSO E. PEPPE, a citizen of the United States, residing in the city of New York, borough of Manhattan, in the county and State of New York, have invented a certain new and useful Improvement in Can-Carriers, of which the following is a specification.

The invention relates to wheeled carriers for use by street sweepers, and the object of the invention is to provide a carrier adapted to receive and hold two cans, approximately balanced one against the other, which shall be of simple economical construction, of few parts, and easily operated.

The invention consists in certain details of construction and arrangement by which the above objects are attained, to be hereinafter described.

20 The accompanying drawings form a part of this specification and show the invention as it has been carried out in practice.

Figure 1 is a side elevation of the improved carrier with two round cans in place thereon. Fig. 2 is a corresponding plan view, two round cans being indicated by dotted lines, and a square can also thus outlined. Fig. 3 is an end elevation with the cans omitted. Fig. 4 is a vertical longitudinal section 25 through the platform of the carrier alone. Fig. 5 is a plan view of the same. Fig. 6 is an elevation of one of the side-frames or standards. Fig. 7 is a corresponding vertical section on the line 7—7 in Fig. 6. Fig. 8 is a side view of the lower end of one of the handles.

Similar letters of reference indicate the same parts in all the figures.

40 A is the platform of the carrier, made in a single casting in the form of an open frame having large openings α α provided therein for lightness, and having a step or offset at Λ^1 to provide two horizontal portions of differing height, each adapted to support a 45 cam M thereon.

A^2 A^3 are downwardly projecting arms on the under face of the platform near the front, adapted to serve as bearings for two small wheels or rollers B B normally elevated out 50 of contact with the street surface, and serving to support the lower front end of the platform when the low end is depressed.

A^3 is an apron or flange extending downwardly from the margins of the platform 55 and serving to stiffen it. On the vertical rear face of such flange is pivoted a strut C

having downwardly projecting legs C^1 C^1 arranged to serve as a support for the rear high end of the platform when required. An arm or hook C^2 on the strut engages a 60 pin A^5 on the flange and maintains the strut in position for service. When not required it may be partially revolved on its pivot A^4 until its center of gravity passes the vertical and is thus maintained in the elevated position resting against the pin A^5 until again turned down for service.

D D are suspension side frames, each in a single casting comprising a central vertical standard and curved braces D^1 D^1 extending downwardly therefrom. The lower end of the standard is riveted to the side-flange A^3 of the platform as at d and to a wing A^6 or extension of said flange as at d^1 . The upper end of each standard terminates in a head D^2 which is hollowed to form a socket d^2 in which is received the lower end of a curved bar E serving as a handle for the propulsion of the carrier, and such lower end is provided with a series of holes e e arranged to receive the end of a screw D^3 located in the outer face of the head in position to engage either of such holes as presented and thus permit the handles to be adjusted as to height. The socket d^2 is open at the lower end as shown to facilitate the removal of the casting-core and any refuse matter entering such socket. Below the socket and the junction of the curved braces D^1 D^1 with the head D^2 is a rectangular offset d^4 receiving the square transversely extending axle F which is secured in place by the clips F^1 F^1 extending through suitable holes d^5 in the standard and receiving nuts F^2 on their ends. On 80 the outer overhung ends of the axle are the wheels G, of sufficient diameter to support the platform above the road surface with its rollers B B and strut C slightly elevated above such surface when the platform is in the horizontal position. The standards D D with their curved arms or braces D^1 D^1 thus suspend the platform and its cans and permit them to be easily moved about on the wheels G as required, and by 85 locating the two cans on opposite sides of the axle the load is balanced and its transportation effected with but little labor.

Wings D^4 D^4 on the head of each standard afford means for riveting longitudinally extending bars H H at about the mid-height 100 of the cans, serving to hold the latter against

lateral displacement, and equipped with hooks H^1 H^1 at their ends to which loops J J of chain are separably connected to insure against accidental movement longitudinally of the platform.

The adjustability of the handles E E permits them to be conveniently placed for ease of operation.

It will be noted that the platform is a single casting, as is also each of the standards D D and its branches, and but few rivets are required in strongly and stiffly connecting these parts. The offset in the platform is for the purpose of receiving a lower or battered can on the high portion, with a full length can on the low portion, thus bringing the mouths of both to approximately the same level. By employing two cans they may be used to receive refuse each of different character to conform to the separation requirements of the municipal rules.

I claim:—

1. In a carrier of the character set forth, a platform comprising a single casting, an axle extending transversely of and above said platform, wheels on said axle, standards secured to said axle and platform and suspending the latter, braces on said standards, attached at their lower ends to said platform at separated points, each of said

standards and its braces comprising a single casting having a socket in its upper end, and handles adjustably mounted in such sockets.

2. In a carrier of the character set forth, a platform comprising a single casting and having one portion of its upper face higher than the remaining portion, and each of such portions adapted to support a can, an axle extending transversely of said platform above the latter, standards secured to said axle and platform and suspending such platform, braces on said standards cast in one therewith, a stiffening flange on the margins of said platform, a strut pivotally connected to such flange at the rear of the said higher portion of said platform, a head on the upper end of each standard and having an opening therein serving as a vertical socket, handles received in such sockets, and a screw on the side face of such head, said handles having a series of holes adapted to receive the ends of said screws and permit the height of said handles to be adjusted.

In testimony that I claim the invention above set forth I affix my signature, in presence of two witnesses.

ALPHONSO E. PEPPE.

Witnesses:

CHARLES R. SEARLE,
AGNES M. KOMMER.
